UNITED STATES PATENT OFFICE.

NORMAN F. LEHR, OF ROCHESTER, NEW YORK, ASSIGNOR TO EASTMAN KODAK COMPANY, OF ROCHESTER, NEW YORK, A CORPORATION OF NEW YORK.

DESIGN FOR A CAMERA CASING.

Application filed November 9, 1926. Serial No. 19,653. Term of patent 14 years.

To all whom it may concern:

Be it known that I, NORMAN F. LEHR, citizen of the United States, residing at Rochester, in the county of Monroe and State of New York, have invented a new, original, and ornamental Design for a Camera Casing, of which the following is a specification, reference being had to the accompanying drawing, forming a part thereof.

In the drawings Fig. 1 is a top view of the camera casing showing my new design;

Fig. 2 is a side view of the camera casing shown in Fig. 1 showing my new design; and Fig. 3 is an end elevation of the camera casing shown in Fig. 1.

I claim:

The ornamental design for a camera casing, as shown.

Signed at Rochester, New York, this 4th day of November, 1926.

NORMAN F. LEHR.
